UNITED STATES PATENT OFFICE.

WILLIAM F. HUTCHISON, SR., OF FORT WORTH, TEXAS, ASSIGNOR OF ONE-THIRD TO JOE PLESCHIA AND ONE-THIRD TO CECIL O. HUTCHISON, BOTH OF FORT WORTH, TEXAS.

INDICATOR FOR VEHICLES.

1,326,510.

Specification of Letters Patent. Patented Dec. 30, 1919.

Application filed April 11, 1916. Serial No. 90,371.

To all whom it may concern:

Be it known that I, WILLIAM F. HUTCHISON, Sr., a citizen of the United States, residing at Fort Worth, in the county of 5 Tarrant and State of Texas, have invented certain new and useful Improvements in Indicators for Vehicles, of which the following is a specification.

My invention relates to indicators and 10 more particularly to indicators for moving vehicles, and the object is to provide a simple and inexpensive indicator which can be easily operated and to provide a device for preventing accidents and to avoid danger.

15 A person using an automobile is required to give some sign when he is going to stop or make a turn. This is done usually with the hand. The object of this invention is to provide a device to take the place of 20 the hand and which will be much more efficient than the hand and which can be used where the hand cannot be used. The advantage is that the person using the vehicle can operate a sign on either side of 25 the vehicle with very little effort and attention. Other objects and advantages will be fully explained in the following description and the invention will be more particularly pointed out in the claims.

30 Reference is had to the accompanying drawings which form a part of this application.

Figure 1 is a diagrammatic elevation of the improved indicator set forth herein. 35 Fig. 2 is an elevation of one of the indicators, showing in detail the operating mechanism. Fig. 3 is a diagrammatic view of the make and break contacts.

Similar characters of reference are used 40 to indicate the same parts throughout the several views.

Indicators are set forth herein which can be mounted, one on each side, of a vehicle. Casings 1 and 2 are provided to contain the 45 indicators and their operating mechanism. These casings are to be attached to the vehicle in any suitable manner and in any desirable position. Push buttons 3 and 4 are provided for operating the indicators and 50 these push buttons can be placed near the seat of the driver or chauffeur. A battery 5 may be located at any desirable position. A solenoid 6 is located in each casing 1 and 2. The solenoid is provided with the usual

plunger armature 7. A standard 8 is 55 mounted on and made rigid with the solenoid casing. A block lever 9 is fulcrumed on the standard 8. A link bar is pivotally connected to the plunger armature 7 and to the block lever 9. A tubular arm 10 is 60 made rigid with the lever 9 and a lamp socket 12 for electric lamp 11 is attached to the arm 10. Contacts 13, which may be of spring metal, are attached to the lever 9 which should be of some non-conducting 65 material. Wires 14 are attached to these contacts 13 and run through the lever 9 and through the arm 10 and connected to the socket 12 in the usual manner of making electrical connection with lamp sockets. 70

Wires 15 and 16 are electrically connected with the battery 5 and to the solenoid 6 for energizing the solenoid. Wires 17 and 18 are connected to the wires 15 and 16 respectively and extended upwardly and into 75 the standard 8 and electrically connected to contacts 19 which are attached to the standard 8. A collar 20 is attached to the socket 12 for the purpose of attaching a globe 21 for protecting the lamp 11. The globe 21 80 is preferably made in the form of a hand which can be plainly seen in the dark or in the light. Duplicate mechanism is mounted in the casing 2 and wires 22 and 23 are connected respectively with wires 15 85 and 16 for the solenoid 6 in casing 2 and wires 24 and 25 are connected to wires 22 and 23 respectively for the light circuit in casing 2. The casing 1 may be mounted on one side of the vehicle and the casing 2 90 mounted on the other side of the vehicle. Various changes in the sizes, proportions and arrangements of the several parts of the mechanism herein shown may be made without departing from my invention. 95

The operation is as follows: Pressure on the button 3 will energize the solenoid 6. The armature 7 will be drawn down into the solenoid and by means of the link bar 26, the lever 9 will be drawn down until 100 the contacts 13 are brought against the contacts 19 which action will close the circuit for the lamp 11. At the same time, the arm 10 will be thrown to a substantially horizontal position, as indicated in Fig. 1. Just 105 as the arm 10 reaches the horizontal position, the circuit is closed by the contacts and the lamp 11 is illuminated. As soon as the

pressure is taken from the button 3, the circuit through the solenoid 6 and the lamp circuit will be broken.

I claim:—

- 5 1. An indicator for vehicles comprising a solenoid, a standard fixed on said solenoid, a housing for said solenoid and said standard, a lever fulcrumed on said standard and adapted to swing into and out of said housing, a lamp carried on one end of said lever and contacts carried on the other end thereof, coöperating contacts mounted on said standard, a lamp circuit consisting of wires in part carried by said lever and connected 10 to the lamp and to the contacts on said lever and in part carried by said standard and connected to the contacts on said standard, a movable armature for said solenoid and a link-bar pivotally connected to said armature and to said lever, and means for energizing said solenoid for raising said lamp out of said housing and automatically closing said lamp circuit.
- 15 2. An indicator for vehicles comprising

a housing, a solenoid fixedly mounted therein, a source of electricity, electrical connection of said solenoid with said source of electricity, a movable armature operating in said solenoid, a standard rigid with said solenoid, a block pivoted on said standard, 20 a pair of contacts carried by said block, a tubular arm carried by said block adapted to swing into and out of said housing, signaling devices consisting of a hand carried by said arm and a lamp carried by said hand, wires connecting said lamp and said contacts a pair of contacts mounted on said standard and electrically connected with said source of electricity, and a link-bar pivotally connected to said block and to said armature and adapted to draw the contacts on said block into electrical connection with the contacts on said standard and to draw said hand into signaling position.

In testimony whereof, I set my hand this 45
8th day of April, 1916.

WILLIAM F. HUTCHISON, SR.
